UNITED STATES PATENT OFFICE.

CLEVELAND H. SCHENK, OF SPRINGFIELD, ILLINOIS.

AUTOMATIC SHUT-OFF FOR GAS-BURNERS.

1,074,211.

Specification of Letters Patent. Patented Sept. 30, 1913.

Application filed July 29, 1913. Serial No. 781,710.

To all whom it may concern:

Be it known that I, CLEVELAND H. SCHENK, a citizen of the United States, residing at Springfield, in the county of Sangamon and State of Illinois, have invented a new and useful Automatic Shut-Off for Gas-Burners, of which the following is a specification.

This invention relates to gas burners and the purpose of the invention is to provide simple and effective means to automatically shut off the gas in case the light is blown out while the gas is turned on.

The invention is illustrated in the annexed drawing and is hereinafter particularly described and the novel features thereof are finally recited in the claims.

Figure 1 is a side elevation of the apparatus; Fig. 2 is a vertical longitudinal section through the casing on the line X X of Fig. 20 1 and shows in elevation the parts within the casing; and Fig. 3 is an enlarged horizontal transverse section on the line Y. Y. of Fig. 1.

Similar reference numerals designate like parts in the different views.

A service pipe 1 conveys gas from the source of gas-supply to the burner. A valve 2 having a tapered plug 3 is connected with the pipe 1. The plug 3 has a longitudinal bore 3^a accommodating the stem 4. A polygonal stem 4 is fitted to slide longitudinally in the bore 3^a. A push button 5 secured at the lower end of the stem serves as a handle for sliding the stem in the plug and 30 rotating the plug. A nipple 6 connects an elbow 7 with the valve 2. A valve 8 connected with the elbow 7 has a tapered horizontal rotative plug 9.

An angular lever designated as a whole 40 by the numeral 10 comprises a horizontal member 10^a and an upwardly inclined member 10^b. The lever is connected with and adapted to rotate the plug 9. The horizontal member 10^a normally rests on the upper end 45 of the stem 4. The member 10^b has a hole 10^c adapted to accommodate the spring 13. A burner 12 is connected with the valve 8.

The thermostatic controlling device controlling the closing of the valve 8 will now 50 be described. A spring 13 has its upper part fixed on the burner 12 and its lower part extends downwardly through the hole 10^c. Near the lower end of the spring 13 is a shoulder 13^c. When the lever 10 is in its 55 normal position, the free part of the spring extends downwardly through the hole 10^c.

The shoulder 13^c is below the member 10^b, and the spring is slightly compressed. A stationary rigid metal casing 14 incloses the lever 10, the spring 13 and the lower part 60 of the burner 12. The lower end of a coiled spring 15 is connected with the outer end of the member 10^a and its upper end is connected with the casing 14. If upward pressure be applied on the button 5 it will cause 65 the stem 4 to slide upward to raise the member 10^a and cause compression of the spring 15, and when the pressure on the button is discontinued the spring will act to depress the member 10^a and return the stem 4 to its 70 initial position. The upward movement of the member 10^a will cause downward movement of the member 10^b. During the downward movement of the member 10^b the end wall of the hole 10^c acting on the inclined 75 upper surface 13^b of the cam 13^a will cause further compression of the spring 13 until the member 10^b passes the lower end of the part 13^a, whereupon the spring 13 will act to cause the shoulder 13^c to engage the member 80 10^b and hold it in its depressed position.

A slightly concave plate 16 of zinc or other metal expansible to a relatively large extent by the application of heat, is supported in the casing adjacent to the tip of the burner 85 12. The ends of the plate are in close contact with the rigid casing which prevents longitudinal movement of the plate. The lateral edges of the plate are close to but do not touch the side walls of the casing, in order 90 that the central part of the plate may be free to move rearwardly upon the heating of the plate and forwardly upon the cooling of the plate. The front of the plate is slightly concave in order to determine the 95 direction of movement of the central part of the plate. When the plate is heated by the flame, the ends of the plate being immovable, the expansion of the metal will cause the plate to buckle inwardly to produce horizontal inward movement of the central part 100 of the plate and the cooling of the plate will cause reverse movement of the plate.

A lever 17 is mounted to oscillate on a pivot 18. Adjacent to the upper end of the 105 lever 17 is a longitudinal slot 17^a which accommodates a rivet 19 or equivalent connecting device, connecting the upper part of the lever with the central part of the plate 16 in such manner that the buckling of the 110 plate will cause the upper end of the lever to move inward and the slot in the lever will

permit slight sliding of the upper part of the lever on the inner face of the plate to prevent binding of the lever on the plate. When the member 10^b is depressed, the 5 lower end of the lever 17 is a little above the upper surface of the member 10^b.

The operation of the device is as follows: Preliminary to lighting the gas the stem 4 will be pushed upward to move the lever 10 10 to compress the spring 15 and to open the valve 8. When the stem 4 has been pushed upward to the full extent it will be rotated to rotate the plug 3 to open the valve 2 to the desired extent, and both valves being 15 open, gas from the pipe 1 will flow through the valves to the burner 12 and the gas will then be lighted. The upward movement of the member 10^a will cause the member 10^b to move downward until the free end of 20 the member 10^b passes the shoulder 13^c and thereupon the spring 13 will act to project the shoulder 13^c above the member 10^b and the shoulder 13^c will hold the member 10^b in its depressed position and cause the raised 25 member 10^a to keep the spring 15 compressed. The flame from the burner 12 will heat the plate 16 and cause it to expand and the expanding of the plate 16 will cause the upper end of the lever 17 to 30 move to the left and its lower end to move to the right and compress the spring 13 to disengage the shoulder 13^c from the member 10^b and release the member 10^b so that it will move slightly upward and stop against 35 the lower end of the lever 17 and the lever will then prevent further upward turning of the member 10^b. If the light be then extinguished without closing the valve 2 the plate 16 will be cooled by the surrounding 40 air and the cooling will cause contraction of the plate and the contracting of the plate will cause the upper end of the lever 17 to move to the right and the lower end of the

lever to move to the left out of the path of the member 10^b and thereupon the spring 45 15 will act to push the member 10^a downward and cause the plug 9 to rotate to close the valve 8 and shut off the gas.

Having fully described my invention what I claim is new and desire to secure by Letters Patent is:

1. The combination of a burner; a valve controlling the supply of gas to the burner; a first lever adapted to operate said valve; a first spring adapted to engage said lever to 55 keep the valve open; a second spring effective to move said lever to close the valve; a casing in fixed relation to the burner; an expandible plate mounted in the casing and adapted to buckle upon the heating of the 60 plate and move reversely upon the cooling of the plate; and a second lever connected with said expandible plate and adapted to disengage said first spring from said first lever upon the cooling of said expandible 65 plate.

2. The combination of a first valve-casing; a plug rotative in said valve-casing; a stem adapted to slide longitudinally in said plug; a second valve-casing in communication with said first valve-casing; a plug rotative in said second valve-casing; a lever connected with the plug in said second valve-casing and operable by said stem; a burner in communication with said second 70 valve-casing; a spring latch adapted to engage said lever; means for releasing said spring latch; and a spring adapted to move 75 said lever.

In witness whereof I have hereunto signed my name at Springfield, Illinois, this 26th day of July, 1913.

CLEVELAND H. SCHENK.
